UNITED STATES PATENT OFFICE.

FRANK K. ARNOLD, OF NASHUA, NEW HAMPSHIRE, ASSIGNOR TO NASHUA CARD GUMMED & COATED PAPER COMPANY, OF NASHUA, NEW HAMPSHIRE, A CORPORATION OF MASSACHUSETTS.

COIN-HOLDING CARD.

1,034,564.

Specification of Letters Patent.

Patented Aug. 6, 1912.

Application filed January 9, 1912. Serial No. 670,267.

To all whom it may concern:

Be it known that I, FRANK K. ARNOLD, a subject of the King of Great Britain, and a resident of Nashua, in the county of Hillsboro and State of New Hampshire, have invented certain new and useful Improvements in Coin-Holding Cards, of which the following is a specification.

This invention relates to means for facilitating the transportation of coins by mail, and refers particularly to that type of coin carrier or holder which consists of a flat member comprising one or more thicknesses of card board said members having slits or slots, through which the coin may be partially inserted so as to be retained therein and held from shifting about in an envelop inclosing a card.

The object of the invention is to provide a simple and practical device of the character mentioned which can be manufactured at an exceedingly low cost, and to these ends my invention consists in the card constructed substantially as hereinafter described and claimed.

Of the accompanying drawings,—Figure 1 is a plan view of a card constructed according to my invention, the position which the coin would occupy when assembled with the card being indicated by a dotted circle. Fig. 2 is a view similar to Fig. 1, illustrating a modification. Fig. 3 represents a section on line 3—3 of Fig. 2 and showing a coin in place.

Similar reference characters indicate the same or similar parts on all of the views.

Referring first to Fig. 1, a card of suitable material, such as paste-board, is indicated at 5. Preferably at substantially the center of the card there are formed angular slots or slits as indicated in said figure. The slit 6 which will be referred to hereinafter as the entrance slit, is a reentrant one. In other words, there are two slits which meet each other at an angle, said slits being parallel with radii of the circular space that is to be occupied by the coin. Two other slits 7—7 are formed which are also reentrant angles, and for purposes of distinction, they will be referred to hereinafter as the supporting slits. The formation of the slits as shown results in providing a bridge piece or guard 8 having three radial arms, said bridge piece being, of course, integral with the body of the card. It will be observed

that each arm of the entrance slot 6 is longer than the adjacent arm of the slit 7, so that two lines drawn from the two ends of slit 6, down to the ends of the slits 7, below, would be substantially parallel. This is so that 60 when the coin indicated by dotted lines is inserted through the slit 6 in the direction of the arrow, such act will not tear or extend the entrance slit 6.

The coin is assembled with the card by 65 pushing it through the slit 6, under the bridge piece 8 and then upwardly, through the slit 7, until the lower end of the coin nearly reaches the lower end of the two reentrant angle slits 7, the coin then having 70 one face supported by the triangular portions of the body of the card that project into the reentrant angles of the slits, the upper face of the coin being held by the three-armed bridge piece 8.

For many purposes the coin will be sufficiently held by friction, but I prefer to provide means for preventing any possibility of the coin returning toward the direction from which it was inserted. To attain this 80 object, I form a detent tab 9 by means of a U-shaped cut so that after the coin has been inserted into the position described, and as indicated by the dotted circle in Fig. 1, the tab 9 can be pushed upwardly and sprung 85 past and above the upper edge of the coin, thereby locking the coin securely in place under the bridge piece 8.

It will be noticed that the slits 6 and 7, are not formed by single line cuts, but are 90 formed by removing some of the material of the card. This renders it easier to insert the coin as described and reduces liability of tearing or lengthening the ends of the slits.

The card as described can easily be manufactured by a single operation of properly constructed dies, which dies may also carry means for impressing in the surface of the card an arrow to indicate the point from 100 which the coin should be started and the direction in which it should be moved when assembling, and the dies may also impress in the surface of the card suitable words to indicate where the coin may be inserted, and 105 also the denomination of the particular coin for which the card is intended.

Figs. 2 and 3 illustrate a slight modification which, however requires the use of a double card or a backing under the main 110

card. In this form the card 5 is cut out to form three segmental slots 10. The ends of the slits 11 and 12 are formed the same as the ends of the slits 6 and 7 in Fig. 1, said 5 slits extending beyond the outer edges of the segmental slots 10 so that the resulting bridge piece 13 may be deflected upward sufficiently to permit a coin of the proper size to be slipped into the pocket formed 10 under the bridge piece, the edge of the coin fitting within the outer margin of the three slots 10. The two entrance slits 11 are longer than the slits 12 for the same purpose as hereinbefore described in connection 15 with the entrance slit 6 of the form shown in Fig. 1.

When the diameter of the pocket provided by the three segmental slots 10 under 20 the bridge piece 13 is greater than that of the coin to be used in connection with this structure, it is essential that a backing be provided to prevent the coin from dropping through. Such backing as illustrated in Fig. 20 is a card 14 which is adhesively secured to 25 the main card 5, but of course not secured to the card 13. If the coin is larger than the diameter of the pocket provided by the segmental slots 10 then no backing such as at 25 14 will be necessary. It will be seen that in 30 each form I have provided a structure wherein the card has three radial pairs of

slits, the slits of each pair being substantially parallel, thereby providing a bridge piece which comprises three radial arms that are integral with the card. The card 35 so constructed can be made at an exceedingly low cost and it will firmly hold the coin to prevent any lateral slipping. And the assemblage of the coin with the card can be easily effected. By forming the entrance 40 slit or slits longer than the others, the assemblage is facilitated without detracting from the capability of the device to securely retain the coin in place.

I claim:—

1. A card slotted to form three flaps and a three-armed bridge-piece, the middle of each flap lying opposite the arm of the bridge-piece between the other two flaps.
2. A card slotted to form three flaps and a three-armed bridge-piece, the middle of each flap lying opposite the arm of the bridge-piece between the other two flaps, means being provided for locking a coin under the bridge-piece.

In testimony whereof I have affixed my signature, in presence of two witnesses.

FRANK K. ARNOLD.
